[57] ABSTRACT

Hypolipidemic agents of the formula

wherein

R° and R are independently hydrogen, halo, alkyl, alkoxy or CF₃, and

Y and Y' are independently hydrogen, halo, alkyl, alkoxy or CF₃.

13 Claims, No Drawings

**TREATING LIPIDEMIA WITH
1-TERTIARY-BUTYL-3-ARYL-2,1-
BENZISOXAZOLINES AND COMPOSITIONS
THEREFOR**

Tertiary-butyl-3-aryl-2,1-benzisoxazolines have previously been disclosed as valuable intermediates in U.S. Pat. No. 3,541,151. To our knowledge, no pharmacological activity has been heretofore associated with such compounds.

The present invention involves the discovery that certain 1-tertiary-butyl-3-aryl-2,1-benzisoxazolines exhibit pharmacological properties. More specifically, it has been found that these compounds possess hypolipidemic properties, making them especially suitable for incorporation into pharmaceutical compositions.

According to this invention, a hypolipidemic effect is displayed by compounds of formula I:

wherein
 R^o and R are independently hydrogen, halo of atomic weight of from 18 to 80, lower alkyl of 1 to 4 carbon atoms, lower alkoxy of 1 to 4 carbon atoms and trifluoromethyl, and
 Y and Y' are independently hydrogen, halo of atomic weight of from 18 to 80, lower alkyl of 1 to 4 carbon atoms, lower alkoxy of 1 to 4 carbon atoms or trifluoromethyl.

The compounds of formula I may be prepared in accordance with the two-step procedure disclosed in U.S. Pat. No. 3,541,151, alluded to above. Essentially, the procedure involves the following reaction scheme:

wherein R^o, R, Y and Y' are as defined above.

The preparation of compounds III by the reaction of Step 1 may be carried out at temperatures in the range of from 0°C. to 60°C., preferably 10°C. to 35°C., and conveniently at about room temperature. A strong inorganic acid adapted to form a crystalline quaternary salt is required. Acids of this type are known, and include by way of illustration, tetrafluoroboric acid and perchloric acid. The reaction is carried out in the presence of an organic solvent which is inert and adapted to dissolving the reactants and product compound of Formula III. Suitable solvents are known and available, and include by way of illustration, the nitrated hydrocarbons, e.g., nitromethane. The resulting reaction product of Formula III may be isolated from the reaction of Step 1 by working up by conventional techniques.

The preparation of compounds I involving the reduction of compound III is desirably effected with a suitable borohydride as the reducing agent, more desirably, an alkali metal borohydride such as sodium borohydride, followed by working up in a manner conventional for borohydride reductions. The reduction may be carried out at temperatures in the range of 0°C. to 80°C., preferably between 15°C. to 30°C. The reaction is carried out in an organic solvent of known type, preferably a lower alkanol such as methanol or ethanol, preferably ethanol. The reaction products of Formula I may be isolated from the reaction mixture of Step 2 by working up by conventional techniques.

The compounds of structural Formula I are useful because they possess pharmacological activity in animals. In particular, the compounds are useful as hypolipidemic agents, as evidenced, for example, by lowering cholesterol and triglyceride blood serum levels in tests on a group of white rats which are given typically 15-250 milligrams per kilogram of body weight per diem of the compound orally, for 6 days, followed by extraction with isopropanol of serum or plasma after anesthetizing the rats with sodium hexobarbital, and then noting the cholesterol and triglyceride contents as compared to those of a control group. The cholesterol and triglyceride contents are determined by the methods described by Lofland, H.B., *Anal. Biochem.* 9:393 (1964); (Technicon method N 24a); and G. Kessler and H. Lederer, *Technicon Symposium, Mediad Inc., New York*, Pages 345-347 (1965), respectively. For such usage, the compounds may be administered orally or parenterally, preferably orally, and in admixture with conventional pharmaceutical carriers. The dosage administered may vary depending upon known variables such as the particular compound employed and the severity of the condition being treated. In general, satisfactory results are obtained when administered at a daily dosage of from about 2 milligrams to about 250 milligrams per kilogram of animal body weight, preferably given orally and in divided doses, 2 to 4 times a day, or in sustained release form. For most mammals the total daily dosage is from about 140 milligrams to about 1,500 milligrams of the compound, and dosage forms suitable for internal administration comprise from about 35 to 750 milligrams of the compound in admixture with a solid or liquid pharmaceutically acceptable carrier or diluent.

65

For above usage, the compounds of structural formula I may be administered orally in such forms as tablets, dispersible powders, granules, capsules, syrups and elixirs; and parenterally as solutions, suspensions, dispersions, emulsions, and the like, e.g., a sterile injectable solution such as an aqueous suspension. These pharmaceutical preparations may contain 0.5 percent up to about 90 percent of the active ingredient in combination with the carrier or adjuvant, more usually between 3 percent and 50 percent by weight. Such compositions may be prepared according to any method known in the art for the manufacture of pharmaceutical compositions, and such compositions may contain one or more conventional adjuvants, such as sweetening agents, flavoring agents, coloring agents and preserving agents, in order to provide an elegant and palatable preparation. Tablets may contain the active ingredient in admixture with conventional pharmaceutical excipients, e.g., inert diluents such as calcium phosphate, calcium sulphate dihydrate, lactose and talc, granulating and disintegrating agents, e.g., starch and alginic acid, binding agents, e.g., starch, gelatin, polyvinyl pyrrolidone and acacia, and lubricating agents, e.g., magnesium stearate, stearic acid and talc. The tablets may be uncoated or coated by known techniques to delay disintegration and adsorption in the gastrointestinal tract and thereby provide a sustained action over a longer period. Similarly, suspensions, syrups and elixirs may contain the active ingredient in admixture with any of the conventional excipients utilized for the preparation of such compositions, e.g., suspending agents (methylcellulose, tragacanth and sodium alginate), wetting agents (lecithin, polyoxyethylene stearate and polyoxyethylene sorbitan monooleate) and preservatives (ethyl-p-hydroxybenzoate). Capsules may contain the active ingredient alone or admixed with an inert liquid or solid diluent, e.g., calcium carbonate, calcium phosphate, kaolin, peanut oil, sesame oil and corn oil. The preferred pharmaceutical compositions from the standpoint of preparation and ease of administration are solid compositions, particularly hard-filled capsules and tablets.

Capsules containing the ingredients indicated below may be prepared by conventional techniques and are useful in reducing the blood levels of cholesterol and triglycerides in mammals at a dose of one capsule 2 to 4 times a day.

Ingredients	Weight (mg.)
1-tertiary-butyl-5-chloro-6-methyl-3-phenyl-2,1-benzisoxazoline	75
kaolin	200

The following examples are merely illustrative of specific compounds of the invention and the manner in which they may be prepared.

EXAMPLE 1

1-Tertiary-butyl-5-chloro-6-methyl-3-phenyl-2,1-benzisoxazoline

5

Step A: Preparation of 1-tert.-butyl-5-chloro-6-methyl-3-phenyl-2,1-benzisoxazolium tetrafluoroborate

To a suspension of 59 g. of 5-chloro-6-methyl-3-phenyl-2,1-benzisoxazole, 26.6 ml. of tert.-butanol and 740 ml. of nitromethane is added dropwise 45.7 g. of a 50 percent aqueous solution of tetrafluoroboric acid. The resulting suspension is stirred at room temperature for 85 hours. The reaction mixture is diluted with approximately 10 liters of diethyl ether and the crystalline precipitate formed is isolated by filtration to yield 1-tert.-butyl-5-chloro-6-methyl-3-phenyl-2,1-benzisoxazolium tetrafluoroborate, m.p. 164°-166°C.

Step B: Preparation of 1-tert.-butyl-5-chloro-6-methyl-3-phenyl-2,1-benzisoxazoline

To a suspension of 24 g. of 1-tert.-butyl-5-chloro-6-methyl-3-phenyl-2,1-benzisoxazolium tetrafluoroborate in 200 ml. of absolute ethanol is added in portions over 15 minutes, 3.5 g. of sodium borohydride. The suspended solid slowly goes into solution and some heat is evolved. The colorless solution is allowed to stand at room temperature for 1 hour, during which time a crystalline precipitate is formed. The mixture is then cooled (ice/water) and diluted with an equal volume of water. The solid so produced is isolated by filtration and recrystallized from 50 percent aqueous ethanol to yield 1-tert.-butyl-5-chloro-6-methyl-3-phenyl-2,1-benzisoxazoline, m.p. 114°-115°C.

EXAMPLE 2

1-Tertiary-butyl-5-chloro-3-phenyl-2,1-benzisoxazoline

Step A: Preparation of 1-tert.-butyl-5-chloro-3-phenyl-2,1-benzisoxazolium tetrafluoroborate

To a suspension of 5-chloro-3-phenyl-2,1-

6

benzisoxazole, 19 ml. of tert.-butanol and 250 ml. of nitromethane is added dropwise 32 g. of a 50 percent aqueous solution of tetrafluoroboric acid. The resulting suspension is stirred at room temperature for 24 hours.

5 The reaction mixture is diluted with 1.5 liters of diethyl ether and the crystalline precipitate formed is isolated by filtration to yield 1-tert.-butyl-5-chloro-3-phenyl-2,1-benzisoxazolium tetrafluoroborate, m.p. 112°-114°C.

10 **Step B: Preparation of 1-tert.-butyl-5-chloro-3-phenyl-2,1-benzisoxazoline**

To a suspension of 8 g. of 1-tert.-butyl-5-chloro-3-phenyl-2,1-benzisoxazolium tetrafluoroborate in 135 ml of absolute ethanol is added, in portions over 15 minutes, 1 g. of sodium borohydride. The suspended solid slowly goes into solution and some heat is evolved. The colorless solution is stirred for 1 hour at room temperature, during which time a crystalline precipitate is formed. The precipitate is washed with water and methylene chloride, and the methylene chloride layer separated, dried, evaporated in vacuo to dryness and the residue recrystallized from ether/hexane to obtain 1-tert.-butyl-5-chloro-3-phenyl-2,1-benzisoxazoline, m.p. 65°-67°C.

EXAMPLE 3

Following essentially the procedure of Example 2 and using in place of 5-chloro-3-phenyl-2,1-benzisoxazole in Step A, an equivalent amount of

- a. 6-methyl-3-phenyl-2,1-benzisoxazole,
- b. 5-bromo-6-methyl-3-phenyl-2,1-benzisoxazole,
- c. 5-bromo-3-phenyl-2,1-benzisoxazole,
- 35 d. 5-chloro-6-ethyl-3-phenyl-2,1-benzisoxazole,
- e. 6-ethyl-3-phenyl-2,1-benzisoxazole,
- f. 5-bromo-6-ethyl-3-phenyl-2,1-benzisoxazole, there is obtained
- a. 1-tert.-butyl-6-methyl-3-phenyl-2,1-benzisoxazolium tetrafluoroborate,
- b. 1-tert.-butyl-5-bromo-6-methyl-3-phenyl-2,1-benzisoxazolium tetrafluoroborate,
- c. 1-tert.-butyl-5-bromo-3-phenyl-2,1-benzisoxazolium tetrafluoroborate,
- 40 d. 1-tert.-butyl-5-chloro-6-ethyl-3-phenyl-2,1-benzisoxazolium tetrafluoroborate,
- e. 1-tert.-butyl-6-ethyl-3-phenyl-2,1-benzisoxazolium tetrafluoroborate,
- f. 1-tert.-butyl-5-bromo-6-ethyl-3-phenyl-2,1-benzisoxazolium tetrafluoroborate, respectively.

EXAMPLE 4

Following essentially the procedure of Example 2, and using in place of 1-tert.-butyl-5-chloro-3-phenyl-2,1-benzisoxazolium tetrafluoroborate in Step B, an equivalent amount of the respective compounds obtained in Example 3, there is obtained

- a. 1-tert.-butyl-6-methyl-3-phenyl-2,1-benzisoxazoline,
- b. 1-tert.-butyl-5-bromo-6-methyl-3-phenyl-2,1-benzisoxazoline,
- 60 c. 1-tert.-butyl-5-bromo-3-phenyl-2,1-benzisoxazoline,
- d. 1-tert.-butyl-5-chloro-6-ethyl-3-phenyl-2,1-benzisoxazoline,
- e. 1-tert.-butyl-6-ethyl-3-phenyl-2,1-benzisoxazoline,
- f. 1-tert.-butyl-5-bromo-6-ethyl-3-phenyl-2,1-benzisoxazoline, respectively.

What is claimed is:

1. A method for treating lipidemia comprising administering to mammals in need of said treatment an effective amount of a compound of the formula:

wherein

R° and R are independently hydrogen, halo of atomic weight of from 18 to 80, lower alkyl of 1 to 4 carbon atoms, lower alkoxy of 1 to 4 carbon atoms or trifluoromethyl.

Y and Y' are independently hydrogen, halo of atomic weight of from 18 to 80, lower alkyl of 1 to 4 carbon atoms, lower alkoxy of 1 to 4 carbon atoms or trifluoromethyl.

2. The method of claim 1 wherein the compound administered is:

wherein R° and R are defined in claim 1.

3. The method of claim 1 wherein the compound administered is:

wherein R° is as defined in claim 1.

4. The method of claim 1 wherein the compound administered is:

wherein R is as defined in claim 1.

5. The method of claim 1 wherein the compound is administered in a daily amount of from 140 to 1,500 milligrams.

6. The method of claim 1 wherein the compound administered is 1-tertiary-butyl-5-chloro-6-methyl-3-phenyl-2,1-benzisoxazoline.

7. The method of claim 1 wherein the compound administered is 1-tertiary-butyl-5-chloro-3-phenyl-2,1-benzisoxazoline.

8. A pharmaceutical composition in unit dosage form useful in the treatment of lipidemia in mammals comprising as the active ingredient thereof a compound of the formula:

40 wherein

R° and R are independently hydrogen, halo of atomic weight of from 18 to 80, lower alkyl of 1 to 4 carbon atoms lower alkoxy of 1 to 4 carbon atoms or trifluoromethyl, and

45 Y and Y' are independently hydrogen, halo of atomic weight of from 18 to 80, lower alkyl of 1 to 4 carbon atoms, lower alkoxy of 1 to 4 carbon atoms or trifluoromethyl, and a pharmaceutically acceptable carrier therefor, said compound being present in said composition to the extent of from about 35 milligrams to about 750 milligrams.

9. The pharmaceutical composition of claim 8 wherein the compound is:

9

wherein R° and R are as defined in claim 8.

10. The pharmaceutical composition of claim 8 wherein the compound is:wherein R° is as defined in claim 8.

11. The pharmaceutical composition of claim 8 wherein the compound is:wherein R is as defined in claim 8.

12. The pharmaceutical composition of claim 8 wherein the compound is 1-tertiary-butyl-5-chloro-6-methyl-3-phenyl-2,1-benzisoxazoline.**13.** The pharmaceutical composition of claim 8 wherein the compound is 1-tertiary-butyl-5-chloro-3-phenyl-2,1-benzisoxazoline.
